UNITED STATES PATENT OFFICE.

GUSTAV PFANNKUCHE, OF CLEVELAND, OHIO, ASSIGNOR TO THE BRUSH ELECTRIC COMPANY, OF SAME PLACE.

REGULATION OF ALTERNATE-CURRENT GENERATORS.

SPECIFICATION forming part of Letters Patent No. 393,448, dated November 27, 1888.

Application filed December 2, 1887. Serial No. 256,816. (No model.)

To all whom it may concern:

Be it known that I, GUSTAV PFANNKUCHE, of Cleveland, in the county of Cuyahoga and State of Ohio, have invented certain new and 5 useful Improvements in Alternating-Current Dynamos; and I do hereby declare the following to be a full, clear, and exact description of the invention, such as will enable others skilled in the art to which it appertains to 10 make and use the same.

My invention has reference to improvements in alternating-current dynamos, the object being to render such dynamos self-exciting and self-regulating, analogous in this respect to 15 compound constant-potential continuous-current dynamos, whereby the same become adapted for the operation of a system of distribution in which a constant difference of potential is required.

20 My improved dynamo is specially designed for use with such systems of distribution in which the translating devices are, in multiple-arc branches, derived from a main or trunk line, and in which it is designed to maintain a 25 constant difference of potential at the terminals of the derived branches or working circuits, which are frequently at great distances from the generator. In such systems the difference of potential at the brushes of the generator is dependent upon the relation of the external resistance to the total resistance in such manner that 30 when the external resistance increases, the difference of potential at the brushes also increases, while at the same time less current is generated in the armature, and when the external resistance decreases, the difference of potential at the brushes also decreases, and more current is at the same time generated in 35 the armature. From this it becomes clear that in a multiple-arc system of distribution, whenever one or more working branches are opened, provision should be made to decrease the strength of the field-magnets, and whenever additional working-circuits are closed the 40 strength of the field-magnets should be increased, in order to maintain a constant difference of potential. In continuous-current dynamos this result is accomplished automatically by providing the field-magnets with two 45 sets of coils, one set of which is in series with

the armature-coils, and the other set in a shunt across the brush terminals of the dynamo; and the manner in which such dynamos operate to maintain a constant difference of potential under the varying resistance of the external 55 circuit is so well understood by those skilled in the art that a specific explanation is deemed unnecessary.

In a dynamo set forth in a separate application for patent filed by me I have applied the principles of the self-exciting compound dynamo to alternating-current generators, whereby the latter become adapted to the feeding of a system of distribution in which a constant difference of potential is required. In said separate application I have shown an alternating-current dynamo in which two sets of field-coils, one in series and the other in a derived circuit, are charged by the alternating currents generated in the armature after the same have 60 been straightened out by suitable commutators, whereby separate excitors are dispensed with; but in some cases, especially when the currents generated by the machine are of very high tension, which is frequently the case in 65 alternating-current generators, these currents are not well adapted for charging the series coils of the field, and my present invention is designed to overcome this difficulty by reducing the tension of the currents designed to 70 charge one set of field-coils by a suitable induction-transformer the primary coil of which is in series with the armature, while the secondary is in circuit with the set of field-coils which 75 it is designed to charge by the same. Thus 80 one set of field-coils is placed in a local circuit charged inductively by the currents traversing the line, which coils take the place of the series coils of the ordinary compound dynamo, while 85 the other set is in a shunt substantially like 90 the shunt-coils in an ordinary compound dynamo, but charged in the manner set forth in my aforesaid separate application. All this 95 will more fully appear from the following detailed description, in which reference is made to the accompanying drawing, in which I have illustrated my invention mainly in diagram, omitting such details as are readily and necessarily implied.

The alternating-current generator 1 may be 100

of any ordinary or improved construction. It is represented in the drawing as mounted upon a base or platform, 2, upon which standards 3 3, of iron, are bolted, which constitute the yokes 5 of the field-magnets. The armature 4, which is preferably of the Brush type, is mounted upon a shaft, 5, which may be journaled in the standards, and is driven in any suitable manner. The alternating currents generated 10 in this machine are collected by brushes 6 6, bearing upon collecting-disks 7 7, secured to but insulated from the shaft and having the terminals of the armature coils connected therewith. All these parts may be of ordinary construction 15 well understood by those skilled in the art, and need not be specifically described.

The collector-brushes 6 6 are connected with the main or trunk line 8 8, which is tapped at distant points by multiple-arc branches, as indicated at 9 9, &c., in which suitable translating devices, 10 10, &c., are placed. There are two sets of field-coils, 11 and 12, upon the field-magnets. The first set is charged inductively 20 by the full line-currents, and the other directly 25 by currents diverted into a shunt, as will hereinafter more fully appear.

Upon a part of the armature-shaft which projects beyond the frame of the machine are mounted two commutators, 13 and 14, side by 30 side, and each insulated from the shaft. Each of these commutators is composed of two hollow cylindrical blocks, 13' 13² and 14' 14², respectively, each of which is provided at one end with a number of segmental teeth alternating with segmental spaces, and each pair of blocks is so mounted upon the armature-shaft that the teeth of one engage the corresponding spaces on the other, with insulating material (indicated by heavy lines) intervening 35 between the two blocks.

There are two pairs of brushes for each commutator, one pair bearing upon the segmental portions and the other pair upon the continuous cylindrical portions thereof, and in the further description these brushes will be referred to as "alternator-brushes" and "straightener-brushes," respectively.

The alternator-brushes 15 15' of commutator 14 are connected by wires 16 and 17, respectively, with the terminals of the secondary coil 18 of a transformer, 19, the primary coil 20 of which is in the main line 8 8, as shown. The alternator-brushes 21 21' of commutator 13 are connected, respectively, with wires 22 and 23, which form a shunt across the collector-brushes 6 6. The straightener-brushes 16' 16² are connected, respectively, by wires 24 and 25 with the terminals of the set of field-coils 11, while straightener-brushes 26 26' are connected, respectively, by wires 27 and 28 with the terminals of the set of field-coils 12.

It must be understood that the total number of segments of each of the commutators is equal to the number of alternations of current in the 65 generator and that they are so located upon shaft 5 relative to the coils of armature 4 that one of the alternator-brushes of each of these

commutators will bear upon a segment of one of the blocks of which it is composed, while the other of these brushes will bear upon a segment 70 of the other of the blocks during the prevalence of one electrical impulse.

The circuits can now be easily traced, and the operation will be readily understood. The alternating currents generated in the armature 4 will pass to the main line 8 8; but a portion of it is shunted by wires 22 23, which portion reaches commutator 13 by alternator-brushes 21 21' and is straightened out by the operation of said commutator. Leaving the latter 80 by one of the straightener-brushes 26 26', the now continuous current passes to and through the set of field-coils 12 and returns by the other of said brushes. The circuit, therefore, which includes the field-coils 12 is strictly a local circuit, similar in this respect to the circuit which includes the shunt-coils of an ordinary compound dynamo, and it will presently be seen that the circuit which includes the set of coils 11 is also entirely a local circuit, different in this 85 respect, essentially, from the circuit including the series coils of an ordinary compound dynamo. The line-currents pass through the primary coil 20 of transformer 19 and act inductively upon the secondary coil 18, generating in 90 the latter alternating currents of comparatively low tension, as is well understood by those skilled in the art. These currents reach commutator 14 by alternator-brushes 15 15', and after being straightened out by the operation 95 of said commutator the now continuous current passes by one of the straightener-brushes 16' 16² and wires 24 25 to and through the set of field-coils 11, which correspond to the series coils of the field-magnet of an ordinary 100 compound dynamo. The regulating effect of this self-exciting alternating-current generator is substantially the same as that of an ordinary compound dynamo, although it is produced in a different manner.

Suppose the machine is 110 running at such rate as to charge the line, which is tapped by a given number of multiple-arc working branches, with the required quantity of current and to produce the required difference of potential. If, now, a number 115 of working-circuits are opened, both the external resistance and the total resistance is increased; but the relation of the external to the total resistance is so changed as to produce an increased difference of potential, while less 120 current is generated in the armature. By reason of the fall of current upon the line less current traverses the primary coil 20 of transformer 19, less current is generated in the secondary coil 18 of said transformer, and the 125 magnetizing effect of the set of field-coils 11 is reduced; but by reason of the increased difference of potential more current than before is diverted into the shunt 22 23, which includes the set of field-coils 12, and the magnetizing 130 effect of these coils is increased. The aggregate effect of the two sets of field-coils, however, is diminished, the field weakened, and the difference of potential is consequently re-

duced, thus re-establishing the original difference of potential. If, on the other hand, additional working-circuits are closed whereby both the external and total resistance are reduced, and the relation of these resistances so changed as to produce a decrease of difference of potential, while at the same time more current is generated. By reason of the increase of current upon the line more current traverses the primary coil 20 of transformer 19, more current is generated in the secondary coil 18 of said transformer, and the magnetizing effect of the set of coils 11 is increased; but by reason of the fall of difference of potential less current than before is diverted into the shunt 22 23, which includes the set of field-coils 12, and the magnetizing effect of these coils is reduced. The aggregate effect of the two sets of field-coils, however, is increased, the field strengthened, and the difference of potential is consequently raised, thus re-establishing the original difference of potential. Thus it will be seen that any change in the system that tends to vary the difference of potential will react upon the dynamo to cause the same to re-establish the original difference of potential. The currents generated in this dynamo will ordinarily be of very high tension, which currents can be sent to great distances over comparatively thin conductors. Such currents, however, are not well adapted for the operation of the more common translating devices—like motors, lamps, &c.—and before reaching such translating devices the original currents should be transformed into currents of lower tension. This may be done by any suitable transformer, and in the drawing I have shown induction-transformers 10 10, &c., with their primary coils in the multiple-arc branches 9 9 and their secondary coils in the working-circuits proper. It will, however, be understood that I am not limited to this arrangement, since other suitable translating devices adapted to be operated by high-tension currents may be substituted for the induction-transformers shown.

Other changes may be made in the general arrangement of the parts without departing from the fundamental idea of my invention. Thus I can charge the set of field coils 12 inductively the same as field-coils 11. This is indicated in dotted lines. In that case I use an additional transformer, 30, the fine-wire primary coil 31 of which is in a shunt from the line with which it is connected by wires 33 and 34. The coarse-wire secondary coil of this transformer is then connected by wires 35 and 36 with the alternator-brushes 21 and 21', respectively, while the shunt-wires 22 and 23 are omitted. Field-coils 12 are thus charged

with straightened low-tension currents, which enable me to use coarse wires for these coils, and which reduce the sparking at the commutator 13.

Having now fully described my invention, I 65 claim and desire to secure by Letters Patent—

1. In a self-exciting alternating-current dynamo, the combination, with a generating-armature and field-magnets provided with two sets of field coils, of an inductorium and a 70 commutator for straightening the secondary currents of the inductorium, and conductors for transmitting such straightened current to one set of field-coils, and a commutator for straightening a portion of the current in the 75 main line, and conductors for transmitting such straightened current to the other set of field-coils, substantially as set forth.

2. In a self-exciting alternating-current dynamo, the combination, with a generating-armature and field-magnets, the latter provided with two sets of field-coils, of an inductorium included in the main line, and a commutator for straightening the secondary currents, and conductor for transmitting such straightened 85 current to one set of field-coils, and a commutator included in a shunt from the main line, and conductors for transmitting the straightened current from said shunt to the other set of field-coils, substantially as set forth. 90

3. In a self-exciting alternating-current dynamo, the combination, with a generating-armature and collectors for taking the alternating electrical impulses from the same, of field-magnets having one set of coils in circuit 95 with the secondary coil of a transformer, the primary of which is in the main line, a second set of field-coils in a shunt across the collectors, and a commutator for each set of field-coils for straightening the currents through 100 the same, substantially as described.

4. In a self-exciting alternating current dynamo, the combination, with field-magnets having two sets of field coils, of an inductorium constructed to transform the current from the main 105 line into secondary currents of reduced tension, and a commutator for straightening the secondary currents to one set of field-coils, and a commutator in a shunt from the main line for straightening the current in the shunt to 110 the other set of field-coils, substantially as set forth.

In testimony whereof I have signed this specification in the presence of two subscribing witnesses.

GUSTAV PFANNKUCHE.
